TYPE BAR MECHANISM FOR TYPEWRITING MACHINES

Elmer L. Wise, Bridgeport, Conn., assignor to Underwood Corporation, a corporation of Delaware

Application December 4, 1944, Serial No. 566,425

10 Claims. (Cl. 197—37)

1

This invention relates to typewriting machines and more particularly to machines in which the type bar mechanism comprises a type head shiftably mounted on the outer end of a type bar and carrying two different types arranged to be brought alternatively into operative position by the shifting of the type head. The invention is illustrated in this application as embodied in a typewriting machine of the Elliott Fisher type having a flat platen.

In Elliott Fisher typewriting machines of the usual construction, certain of the type bars are provided with type heads pivotally mounted respectively on the outer ends of the type bars and each having two types fixed to the head and arranged to be brought alternatively into position to make a type impression on the work sheet supported on the platen, by the shifting of the head from one position to another on the type bar. In such type bar mechanisms the head is locked in one position and is yieldingly held in the other position upon the type bar by means of a leaf spring, the free end of which is arranged to engage the opposite sides of a projection or tail on the head. In shifting from the first position to the other, the head engaging end of the leaf spring is first moved back away from the axis of pivotal movement of the head out of locking position with relation to the tail thereof and the head is then swung on its axis to shift the same to the second position. During this movement of the head, the tail is carried past the free end of the spring and the spring thereafter swings back toward the axis of the head. These leaf springs are made of highly tempered steel and a great deal of trouble is occasioned by the breaking of the springs. A rather elaborate construction, requiring considerable labor and time to apply, has been employed to hold the springs securely on the type bars. The springs and the holding mechanism therefore have been comparatively expensive to manufacture and to apply to a machine and the cost of the spring mechanism has added considerably to the cost of the machine.

One object of the present invention is to improve the construction and mode of operation of type bar mechanisms of the character above described for typewriting machines and to provide a novel and improved mechanism for holding the shiftable type heads in either of their working positions.

Another object of the invention is to provide typewriting mechanisms of the class in which shiftable type heads are mounted on the respec-

2

tive type bars, with means for holding the type heads in either of their working positions, which is much less subject to breakage and may be manufactured and applied to the machines at considerable less cost than prior constructions.

With above and other objects in view the invention consists in a type bar mechanism embodying the novel and improved features, constructions and combinations of parts hereinafter described and particularly pointed out in the claims, the advantages of which will be readily understood and appreciated by those skilled in the art.

The several features of the invention will be clearly understood from the accompanying drawings, illustrating the invention in its preferred form and the following detailed description of the constructions therein shown.

In the drawings—

Figure 1 is a view partly in side elevation and partly in vertical section illustrating certain parts of a typewriting machine of the Elliott Fisher type provided with a type bar mechanism embodying the present invention.

Figure 2 is a detail view in side elevation, with certain parts in section, illustrating a single type bar and certain associated parts of the machine and showing in full lines, the type bar in retracted position, and in dot and dash lines, the type bar in three other positions.

Figure 3 is a view in rear elevation partly broken away, illustrating the single type bar mechanism shown in Figure 2, with the type bar in retracted position, and

Figure 4 is a detail view in side elevation on an enlarged scale illustrating certain parts of the mechanism shown in Figure 2.

The invention is illustrated in this application as embodied in a typewriting machine of the Elliott Fisher type such as that illustrated and described in the patent to Oscar J. Sundstrand, No. 2,239,023, dated April 22, 1941.

The machine illustrated comprises the usual platen frame, not shown, in which is mounted for vertical movement the substantially flat platen

2. A line space frame, also not shown, is mounted for forward and rearward movement upon rails formed upon the side bars of the platen frame. The line space frame is provided with front and rear rails upon which is mounted, for movement in letter-spacing direction and return, a type carriage indicated at 4 supporting the type bar mechanisms. For a full and complete disclosure of the parts above referred to, which are not shown herein, reference may be had to said Patent No. 2,239,023.

The present machine is provided with the usual series of type bar mechanisms. The invention is illustrated in this application as embodied in or applied to only one of these mechanisms since that is considered to be sufficient to give a clear understanding of the invention. The type bar mechanism shown comprises a lever 6 pivoted at 8 to a hanger 9 secured to a semi-circular ring 10 suspended below the deck 12 on the carriage. The type bar mechanism comprises a retracting spring 14 acting on the type lever, which operates to retract the lever and tends to retain the lever in its normal position with a member carried by the type head in engagement with a semi-circular buffer ring 15. The type bar mechanism further comprises an elbow lever 16 pivoted at 18 on a hanger 19 suspended from the deck 12, a link 20 connecting the elbow lever with the lower end of the type lever, a sub-lever 22 pivoted on a bracket 24 extending upwardly from the deck, a link 26 connecting the forward end of the sub-lever with the elbow lever, an intermediate lever 28 pivoted upon a fulcrum bar 30 and connected by a link 32 with the rear end of the sub-lever 22 and a retracting spring 34 acting on the intermediate lever.

In the present machine, the intermediate lever is operated by power to impart the type impression strokes to the type lever. The power mechanism for operating the intermediate lever comprises a radius bar 36 pivoted at 38 on a rod supported on the cover plate 40 of the type carriage, a transmitting link 42 connecting the radius bar with the intermediate lever, a driving link 44 having its lower end pivotally connected at 46 with the radius bar, a continuously rotating fluted shaft 48 and a pawl 50 mounted on the driving link and arranged to be engaged with the fluted shaft. The driving link is acted upon by a coiled spring 52 which tends to swing the same about its pivotal connection with the radius bar in a direction to carry the pawl away from the fluted shaft, this movement being limited by an arresting plate 54. The driving link is swung in the opposite direction to engage the pawl with the fluted shaft by means of a draft link 56 connected with the upwardly extending arm of a key lever 58 pivoted at 60 on the carriage, said link having a shoulder arranged to engage a pin 62 on the driving link to swing said link into position to engage the pawl with the fluted shaft. During the downward movement of the driving link to actuate the type bar, the upper end portion thereof engages, at a point adjacent the end of the downward movement of the link, a contact plate 64, mounted on the supporting plate 66 on the carriage for adjustment toward and from the driving link. The engagement of the driving link with the contact plate limits the swinging movement of the driving link toward the fluted shaft and causes the disengagement of the driving pawl from said shaft as said shaft continues its rotation and the type bar executes the last part of its type-impression stroke under momentum.

Certain of the type bars are provided with two types which are arranged to be brought alternatively into operating position in the manner common in machines of the Elliott Fisher type. The type bar 6 is an example of such a type bar. The type bar and the type head shown in Figs. 1 to 4, inclusive, and the releasing and actuating lever for said head hereinafter described have substantially the same construction, arrangement and mode of operation as the cor-

responding parts illustrated and described in the patent to Foothorap No. 1,119,149, dated December 1, 1914.

Upon the outer end of the type bar 6 is pivoted, 5 on an axis 68, a type head 70 upon which are mounted the types 72 and 74 in the angular relation shown in Figs. 1 and 2. Fig. 1 shows the type head in normal position on the type bar with the type 74 in position to engage the work sheet at the end of a type impression stroke of 10 the type bar. To place the type 72 in operating position, the type head is shifted to the position shown in the two lower dot-and-dash line illustrations of the type bar and certain associated parts in Fig. 2.

The movement of the type head on the type bar in a clockwise direction (Figs. 1 and 2) is limited by the engagement of a stop face 76 on the type head with the type bar 6, and the movement of the type head in a counter-clockwise 20 direction is limited by the engagement of a stop face 78 on the type head with said type bar. The engagement of these respective stop faces with the type bar determines the operating positions of the types 72 and 74.

In the present embodiment of the invention, 25 the machine is provided with mechanism for locking the type head in its normal position and for yieldingly holding said head in its other position with relation to the type bar, comprising a lever 80, pivoted at its inner end to the type bar. This locking lever consists of a strip of sheet metal sufficiently heavy to maintain the same substantially from bending during the shifting 30 of the type head. This lever is pivoted at its inner end, as at 82, to the type bar to swing toward and from the bar. The locking lever 80 is preferably bent into the form shown in Figs. 1 and 2 and, at its outer end, is provided with a locking contact portion 84 extending at an angle to the adjacent portion of the lever and normally positioned to engage a locking face 86 formed on one side of a projection or tail 81 on the type head. The lever 80 is pivoted to the type bar by means of a headed pin 88 fixed to the bar and engaging in a slot 90 in the lever, the head of the pin being spaced from the type bar by a distance sufficient to permit the lever to swing freely toward and from the type bar.

The lever 80 is acted upon by a coiled spring 92 connecting the same with a bracket or clip 94 attached to the type bar. The angle at which the coil spring 92 is placed with relation to the lever 80 is such that it tends to swing the lever 40 toward the type bar and, at the same time, tends to move the lever longitudinally toward the axis of the type bar to maintain the lever longitudinally in position with the pin 88 seated in the inner part of the slot 90, as shown in Figs. 3 and 4.

The clip 94 is preferably made of sheet metal and is provided with an opening at its end nearer the axis of the type lever through which the pin 88 passes and the pin is provided with a shoulder 95 (see Fig. 4) to engage the clip and hold the same against the type bar to anchor the clip to the bar. The clip is formed with two fingers 96 which are bent around the type bar to hold the outer part of the clip to the bar.

In order to steady and guide the lever 80 with 70 relation to the type bar, the clip 94 is formed with two spaced wings 98 between which the lever is located, these wings being arranged to engage the edges of the lever. The lever 80 is formed with shoulders 99 (see Fig. 3) for en-

gagement with the wings 98 on the clip to limit the movement of the lever longitudinally away from the axis of the type bar.

The present mechanism includes a releasing and actuating lever 100 pivoted at 102 on the type head and having a cam face 104 for engagement with the out-turned end 84 of the lever 80 to release the lever from locking engagement with the stop face 86 on the type head. The lever 100 is also formed with a stop lug or projection 106 arranged to engage a stop face 107 on the type head and with an actuating arm 108 for engagement with the vertically adjustable semi-ring 109 to release and shift the type head. This arm also is adapted to engage the buffer ring 15 as the type bar approaches the end of its return movement to restore the type head to normal position. The releasing and actuating lever 100, the vertically adjustable semi-ring 109 and the buffer ring 15 preferably have substantially the same construction as the corresponding elements illustrated and described in applicant's Patent No. 2,334,464, dated November 16, 1943.

The mechanism above described has the following mode of operation, starting with the type bar in retracted position with the type head located on the type bar in position to project the type 74 into engagement with a work sheet supported on the platen 2 as shown in Fig. 1 and in full lines in Fig. 2. With the semi-ring 109 located in elevated position as shown in Fig. 1, out of the path of the arm 108, during the advance of the type bar, the type head is held in normal position on the type bar by the locking engagement of the out-turned end of the lever 80 with the stop face 86 on the tail of the type head and the type 74 is projected into engagement with the work sheet at the end of the downward movement of the type bar, the path of the type 74 being indicated in Figure 1 by the dot-and-dash line, leading from said type. In order to shift the type head during the downward movement of the type bar from retracted position, the semi-ring 109 is depressed into the path of the arm 108 on the lever 100 as shown in Figure 2. This may be done by the means of a manually operable key as shown and described in applicant's Patent No. 2,334,464. With the semi-ring in depressed position as shown in Fig. 2, during the early part of the downward swing of the type bar, the arm 108 on the lever 100 engages said semi-ring and the lever is swung with relation to the type head about the pivot 102 in a clockwise direction, Figure 2. During the first part of this movement of the lever 100, the cam 104 swings the lever 80 out of engagement with the locking face 86 on the type head and the stop projection 106 on the lever then engages the stop face 107 on the type head and the type head is swung upon its axis 68 to locate the type 72 in operative position. During the early part of this movement of the type head, the tail of the type head passes the outer end of the lever 80 and the lever, under the influence of the spring 92, thereafter swings back inwardly toward the type bar, thereby insuring the complete shifting movement of the type head. During this latter movement of the lever, the outer end of the lever engages with the side or face of the tail of the type head opposite that upon which the locking face 86 is formed. Figure 2 shows, in the two lower dot-and-dash line illustrations, the relation of the lever 80, the type head, and the lever 100 after the shifting of

the type head. The type head is maintained in this position with relation to the type bar by the lever 80 during the remainder of the advance movement of the type bar to bring the type 72 into engagement with the work and during the greater part of the retracting movement of the bar. Figure 2 shows, in a dot-and-dash line, leading from the type 72, the path of advance movement of said type after it is shifted into operative position.

The shifting of the type head and the movement of the lever 100 with said head diminishes substantially the distance of the outer end of the arm 108 from the axis of the type bar. Therefore, during the retracting movement of the type bar, the outer end of arm 108 clears the semi-ring 109. The head is shifted back into normal position by the engagement of the arm 108 on the lever 100 with the buffer ring 15 during the last part of the retracting movement of the type bar.

With this construction and arrangement of the lever 80 and the coil spring 92, the lever and coil spring may be readily applied to and removed from the type bar. In applying the lever to the bar, the clip 94 is first anchored to the bar by means of the stud 88, and the arms 96 are bent about the bar, the head of the stud being located in spaced relation to the bar by the engagement of the shoulder 95 with the clip. The lever 80 is then manipulated to engage the stud 88 in the slot 90 in the lever and the coil spring 92 is applied to connect the clip 94 and the spring in the manner shown clearly in Figs. 1 and 2. The axis of the spring thus lies at an oblique angle to the type bar such that the spring tends to swing the lever 80 about its pivotal point 82 toward the type bar and also tends to move the lever longitudinally toward the axis of the type bar to maintain the pin 88 seated in the slot 90.

The locking lever mechanism shown and described in this application is relatively simple in construction and inexpensive to manufacture and no elaborate expensive construction is required to hold the locking lever in place on the type bar. Also the application of the locking lever and actuating and controlling spring requires the expenditure of relatively little labor and time.

The coil spring employed to actuate the locking lever is less expensive to manufacture and has a much longer life than the leaf spring heretofore employed.

It is to be understood that the particular structure shown in the drawings of this application is merely illustrative of the invention and that the invention is not limited thereto but that it may be embodied in other forms within the scope of the claims.

A type bar mechanism similar, in certain respects, to the present mechanism, is shown and described in the copending application of Oscar W. Swanson, Serial No. 631,824, filed November 30, 1945.

Having explained the nature and object of the invention and having specifically described a construction embodying the invention in its preferred form, what is claimed is:

1. In a typewriting machine, a type bar, a type head shiftable mounted on the bar, types carried by said head and arranged to be shifted respectively into and out of operative position by the shifting movement of said head, a lever pivoted on said bar and having a slot in the inner end thereof, means carried by the type bar for engaging in the slot to support pivotally the lever and a spring tending constantly to swing the lever

toward the head and thereby to hold the type head in operating position with relation to the type bar.

2. In a typewriting machine, a type bar, a plural type head shiftably mounted on said bar, types carried by said head, a lever pivoted on said type bar for holding the head in operating position, cooperating means respectively on the inner end of the lever and on the type bar and interfittable by manipulation of the lever for removably supporting the lever pivotally on the bar and a spring for holding the means on the inner end of the lever seated with relation to the cooperating means on the bar and for tensioning the lever toward the bar.

3. In a typewriting machine, a type bar, a type head shiftably mounted on said bar, two types carried by said head and arranged to be shifted alternatively into and out of operative position by the shifting movement of said head, a lever pivoted on said type bar for holding the head in either of said positions, cooperating means respectively on the inner end of the lever and on the type bar and interfittable and separable by manipulation of the lever for removably supporting pivotally the lever on the bar and a coil spring connected with the lever and the type bar for tensioning the lever towards the bar to hold yieldingly the type head in position and for tensioning the lever longitudinally to hold the means on the inner end of the lever seated in interfittng relation with the cooperating means on the bar.

4. In a typewriting machine, a type bar, a type head shiftably mounted on said bar, types carried by said head and arranged to be shifted respectively into and out of operative position by the shifting movement of said head, a pin mounted on said bar, a lever pivoted on the bar for holding the head in operative position with relation to the bar and having a slot at its inner end in which said pin is received to support pivotally the lever on the bar and a spring tending to swing the lever toward the head and to hold the lever in place with the pin seated in said slot.

5. In a typewriting machine, a type bar, a plural type head shiftably mounted on said bar, types carried by said head, a lever pivoted on said bar for holding the head in operating position, a clip secured to the bar and having guides for engaging the sides of the lever, cooperating means on the lever and the type bar for pivotally supporting the lever on the bar so that the lever may be removed from the bar by manipulation of the lever and a spring connecting the lever and said clip and tending to swing the lever toward the bar and to hold the lever in place with relation to the bar.

6. In a typewriting machine, a type bar, a type head shiftably mounted on said bar, two types carried by said head and arranged to be shifted alternatively into and out of operative position by the shifting movement of said head, a lever pivoted on said bar for holding the head in either of said positions, guides carried by the bar for engaging the lever to guide the same during its pivotal movement, cooperating means on the lever and the type bar for pivotally supporting the lever on the bar so that the lever may be removed from the bar by relative displacement of the bar and lever and a spring tending to swing the lever toward the head and to hold the lever in place with relation to the bar.

7. In a typewriting machine, a type bar, a type

head shiftably mounted on the bar, two types carried by said head and arranged to be shifted alternatively into and out of operative position by the shifting movement of said head, a lever pivoted on said type bar and removable from the bar by manipulation of the lever for holding the head in either of said positions, interfittng means carried respectively by the type bar and said lever and disengageable by manipulation of the lever for removably holding the lever in position on said bar, a coil spring tending constantly to swing the lever toward the head and thereby to hold the type head in operative position and guiding means carried by the type bar for holding the lever from lateral displacement during its movements toward and from the type bar.

8. In a typewriting machine, a type bar, a type head shiftably mounted on the bar, types carried by said head and arranged to be shifted respectively into and out of operative position by the shifting movement of said head, a lever for holding the head in operative position with relation to the bar, cooperating means respectively on the inner end of the lever and on the bar and pivotally engaged by manipulation of the lever for removably supporting the lever pivotally on the bar and a spring for maintaining the means on the inner end of the lever yieldingly in interfittng relation with the cooperating means on the bar and for tensioning said lever toward the bar.

9. In a typewriting machine, a type bar, a type head shiftably mounted on the bar, types carried by said head and arranged to be shifted respectively into and out of operative positions by the shifting movements of said head, a member mounted on said bar and having a part engaging said head and arranged to yield as the head is shifted from one position to another for yieldingly holding the head in operative position on the bar and cooperating means respectively on the member and bar and interfittable by manipulation of the member for holding the member removably in place on the bar.

10. In a typewriting machine, a type bar, a type head shiftably mounted on the bar, types carried by said head and arranged to be shifted respectively into and out of operative positions by the shifting movements of said head, a member mounted on said bar having a part engaging said head and arranged to yield as the head is shifted from one position to another for yieldingly holding the head in operative position on the bar and cooperative means respectively on the member and the bar and interfittable by manipulation of the member for holding the member removably in place on the bar comprising a slot in said member and projecting means on the bar for engaging in said slot.
